UNITED STATES PATENT OFFICE.

THOMAS S. PUKERUD, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,339,906.

Specification of Letters Patent. Patented May 11, 1920.

Application filed June 6, 1916. Serial No. 101,966.

To all whom it may concern:

Be it known that I, THOMAS S. PUKERUD, a citizen of the United States, and a resident of Wilkinsburg, in the county of Allegheny 5 and State of Pennsylvania, have invented a new and useful Improvement in Control Apparatus, of which the following is a specification.

My invention relates to controllers for 10 governing the operation of electric motors and particularly to that type of controller having a main and a reverser drum.

The object of my invention is to provide a 15 particularly simple and durable mechanical device for controllers of the above-indicated class that shall effectively accentuate the various positions of the main controller drum and also prevent movement of the 20 auxiliary drum when the main drum is in other than the off position, and shall prevent movement of the main drum when the auxiliary drum is in other than an operative position.

Heretofore, controllers of the above-men- 25 tioned type have been provided with a member to accentuate the various positions of the main controller drum and an additional member to interlock the drums, one with the other, in the manner above set forth.

30 My invention provides a single-piece pawl that effectively interlocks the two control drums and also accentuates the various positions of the main controller drum.

Figure 1 and Fig. 2 of the accompanying 35 drawing are, respectively, a top plan view and a side view, partially in section and partially in elevation, of a controller embodying my invention.

The controller shown in the drawing com- 40 prises a casing 1, a plurality of rotatably mounted drums 2 and 3, a notched star wheel 4, a notched cam 5 and an improved pawl 6.

The drum 2 is rigidly mounted upon a 45 shaft 8 which is shown as partially broken away to more clearly illustrate the invention. The star wheel 4 is rigidly secured to the shaft 8 and is provided with a plurality of notches 9, of substantially equal depth, 50 that corresponds to the various operating positions of the controller drum 2 and a notch 10 of greater depth that corresponds to the off position of the controller drum.

The auxiliary drum 3 is adapted to change 55 the motor connections from those for for-

ward direction of operation to reverse direction of operation and is rigidly secured to a rotatably mounted shaft 11 to which the cam 5 is also attached. The notch 12 of the cam 5, which corresponds to the neutral 60 position of the reverser drum 3, is of less depth than the adjacent notches 13 which correspond to the forward and reverse positions of the drum 3. The pawl 6 is provided with an off-set lug 14 that is adapted 65 to engage the notched portions of the star wheel 4 and thereby accentuate the positions of the main controller drum 2, a lug 15 which is adapted to engage the notched portions of the cam 5 and thereby interlock 70 the auxiliary drum with the main drum, as hereinbefore described, and a transverse slot 16 that is positioned intermediate the lugs 14 and 15. The lug 14 is preferably provided with a roller 17. A pin 18 is se- 75 cured to the casing 1 and is adapted to engage the slot 16 and to thereby prevent longitudinal movement and to restrict lateral movement of the pawl 6 in one direction. One end of a spring 19 is secured to the cas- 80 ing 1 by a pin 20 and the other end thereof is attached to the pawl 6 and biases the same to engagement with the notches of the star wheel 4 and the cam 5.

With the controller drums occupying the 85 relative positions shown in the drawing, an attempt to move the main drum 2 will cause the lug 14 to rise on the adjacent star-wheel tooth until the pin 18 engages the bottom of the slot 16 which, by reason of the shallow 90 slot 12, stops further movement of the lug 14 and thereby prevents the rotation of the drum 2. If, however, the drum 3 be moved to either a forward or a reverse position, the deeper notches 13 will permit of the 95 rise of the lug 14 over the adjacent tooth of the star wheel and thereby allow of the rotation of the drum 2. The spring 19 biases the lug 14 into engagement with each notch 9 and thus effectively accentuates the 100 various positions of the controller drum. The relative shallowness of the notches 9 will not permit of the movement of the cam 5 when the lug 19 is in engagement with other than the notch 10.

From the above description, it will be 105 readily understood that my proposed pawl member will perform the function of effectively accentuating the various controller positions and will also definitely interlock 110

the auxiliary and the main drums against simultaneous rotation.

I claim as my invention:

1. In a controller, the combination with a plurality of rotatably mounted contact-bearing drums, a star wheel rigidly secured to one of said drums, and a notched cam secured to another of said drums, of a single pawl having an intermediate pivotal point and having its respective ends engaging said star wheel and said cam to prevent the simultaneous rotation of said drums and to accentuate the positions of said drums, and a spring having its respective ends attached to said pawl near said pivotal point and to a stationary part of said controller for biasing the pawl to its engaging position.

2. In a controller, the combination with a plurality of rotatable drums, a notched cam rigidly secured to one of said drums, and a star wheel rigidly secured to another of said drums, of a loosely pivotally mounted position-accentuating one piece pawl having its respective ends engaging said notched cam and said star wheel, and a spring for biasing said pawl to engagement with said wheel and cam.

3. In a controller, the combination with a main drum having a star wheel the notches of which correspond to the positions of the controller, and an auxiliary drum having a notched cam, of a functionally integral pawl pivotally mounted at a single point and having one end engaging the notches of said star wheel to thereby accentuate the positions of said main drum and the other end engaging said cam, and a tensile spring acting upon the pawl near said point.

4. In a controller, the combination with a plurality of notched rotatable members, of a single loosely intermediately mounted pawl engaging said members to accentuate the positions thereof and to interlock the said members against simultaneous movement, and a spring acting directly upon the mounting-point.

5. In a controller, the combination with a plurality of notched rotatable members, of a position-accentuating pawl having a slot intermediate its ends, a pin extending through said slot for positioning said pawl and a spring for biasing said pawl to engagement with said rotatable members.

6. In a controller, the combination with a plurality of notched rotatable members, of a pawl tangentially disposed relative to said rotatable members and mounted to have restricted longitudinal movement and lateral movement restricted in one direction, and resilient means for biasing said pawl into engagement with said rotatable members.

7. In a controller, the combination with a plurality of notched rotatable members, of a single pawl tangentially disposed with respect to each of said members, and a tensile

spring attached to a central point of the pawl for resiliently biasing said pawl to engagement with said notched members.

8. In a controller, the combination with a plurality of notched rotatable members, of a pawl tangentially disposed with respect to each of said members and having a lateral slot and a plurality of projections for engaging the notches of said rotatable members to thereby accentuate the positions of said members, a pin extending through said slot to pivotally and slidably mount said pawl, and resilient means for biasing said member to its operative position.

9. In a controller, the combination with a plurality of notched rotatable members, of a position-accentuating pawl tangentially disposed with respect to each of said members, means for preventing longitudinal movement of said pawl and for restraining lateral movement thereof in one direction, and resilient means acting upon the pawl near said first means for biasing said pawl into engagement with said rotatable members.

10. In a controller, the combination with a main drum having a star-wheel secured thereto, and an auxiliary drum having a notched cam, of a single integral position-accentuating pawl adapted to engage said star-wheel and said cam and to lock the auxiliary drum in position except when the main drum is in its "off" position and a tensile spring acting upon a central point of said pawl to effect yielding engagement thereof with said star-wheel and said cam.

11. In a controller, the combination with a drum, a notched wheel secured to said drum and having a notch of greater depth than the adjacent notches, an auxiliary drum, and a notched cam secured to said auxiliary drum and having a notch of less depth than the adjacent notches, of a single-piece position-accentuating pawl adapted to mechanically interlock said auxiliary drum in position for certain positions of said main drum and for locking said main drum in position for a certain position of said auxiliary drum.

12. In a controller, the combination with a main drum having a star wheel, and an auxiliary drum having a notched cam, of a single-piece position-accentuating pawl one end of which has an offset lug adapted to engage said star wheel, the other end of which has an offset lug adapted to engage said cam and a laterally-disposed slot intermediate said lugs, a pin adapted to engage said slot and position said member, and means for biasing said lugs into engagement with said wheel and said cam.

In testimony whereof, I have hereunto subscribed my name this 31st day of May 1916.

THOS. S. PUKERUD.
